CONTACT LENS CASE OR SIMILAR ARTICLE

Joseph A. Hueber and Edward K. Hueber, Penn Valley, and Francis J. Wilcox, Jr., Merion, Pa., assignors to Kelley & Hueber—Contact Lens Specialties, Inc., Philadelphia, Pa., a corporation of Delaware

Filed Nov. 21, 1966, Ser. No. 4,762

Term of patent 14 years

(Cl. D57—1)

Fig. 1

Fig. 2

Fig. 3

Fig. 4

FIG. 1 is a perspective view of a contact lens case or similar article embodying our new design;

FIG. 2 is a top plan view thereof;

FIG. 3 is a side elevational view thereof;

FIG. 4 is a bottom plan view thereof.

The side and end, not shown, have substantially the same appearance as the side and end, respectively, shown.

The dominant features of our design reside in the portions shown in full lines.

We claim:

The ornamental design for a contact lens case or similar article, as shown and described.
